UNITED STATES PATENT OFFICE.

JOHN BRYCE, OF ALLEGHENY COUNTY, PENNSYLVANIA.

DESIGN FOR THE ORNAMENTATION OF GLASS-WARE.

Specification forming part of Design No. 5,742, dated April 2, 1872.

SPECIFICATION.

To all whom it may concern:

Be it known that I, JOHN BRYCE, in the county of Allegheny and State of Pennsylvania, have invented a new and useful Design for Glass Molds; and I do hereby declare the following to be a full, clear, and exact description thereof, reference being had to the accompanying drawing making a part of this specification, which is a sectional view of a glass mold and illustrates my improved design.

To enable others skilled in the art to make and use my improved design, I will describe the same.

My design, as represented on the sides *b* of the mold cavity *a*, shows a Scotch thistle, con-

sisting of the stems *c*, leaves *d*, and flowers *e*, so connected and repeated as to form a wreath. The leaves *d* are striated, so as to represent the lines or striations of the natural leaf, and have a roughened surface.

What I claim as my invention, and desire to secure by Letters Patent, is—

The design described and shown, for the ornamentation of glass-ware.

In testimony whereof I, the said JOHN BRYCE, have hereunto set my hand.

JOHN BRYCE.
